UNITED STATES PATENT OFFICE

100,007

DESIGN FOR A GLASS GOBLET

George Dougherty, Morgantown, W. Va., assignor to Morgantown Glass Works, Morgantown,
W. Va., a corporation of West Virginia

Application February 17, 1936, Serial No. 61,208

Term of patent 7 years

To all whom it may concern:

Be it known that I, George Dougherty, a citizen of the United States, residing at Morgantown, Monongalia County, West Virginia, have invented a new, original, and ornamental Design for a Glass Goblet, of which the following is a specification, reference being had to the accompanying drawing, forming part thereof, in which Figure 1 is a side elevational view of the article showing my design, and Figure 2 a vertical cross section thereof.

I claim:

The ornamental design for a glass goblet as shown.

GEORGE DOUGHERTY.
